Thomas D. Worrell's Stove

N° 937

Patented Aug. 25, 1857

Thomas D. Horrell, of Lowell, Mass;
Letters Patent No. 937, Dated Aug. 25, 1857

The schedule referred to in these Letters Patent, and making part of the same.

To all Persons to whom these Presents shall come:

Be it known that I, Thomas D. Horrell, of Lowell, in the County of Middlesex, and State of Massachusetts, have invented or produced a new and ornamental design, shape or configuration for a stove; and I do hereby declare ^{that} the same, is fully represented in the accompanying drawing which is a front elevation of a stove made in accordance with my design.

In carrying out the said design, I employ the figure of an elephant, his feet resting on an elongated, ornamental base. The back of the animal is surmounted by an ornamental howdah or saddle, and stove body extension and an urn or vase. This design or combination of elephant, base, and stove extension as shown in the drawing, I claim as of my production or invention.

In testimony whereof, I have hereunto set my signature this 24th day of June, A. D. 1857.
